[57] CLAIM

The ornamental design for a combined carton and cover therefor, as shown and described.

DESCRIPTION

FIG. 1 is a top perspective view of a combined carton and cover therefor showing my new design;

FIG. 2 is an exploded perspective view thereof;

FIG. 3 is a top plan view of the carton blank, shown separately for clarity of illustration;

FIG. 4 is a plan view of the cover blank, shown separately for clarity of illustration;

FIG. 5 is a top plan view of the carton, shown with the cover removed;

FIG. 6 is a bottom plan view thereof;

FIG. 7 is a bottom plan view of the cover element;

FIG. 8 is a perspective view of the carton element, shown in an alternate configuration for illustrative purposes;

FIG. 9 is a perspective view of the carton element, shown in a further alternate configuration;

FIG. 10 is a bottom perspective view of the cover element, shown in an alternate configuration for illustrative purposes;

FIG. 11 is a side elevational view of the carton assembly, the side opposite being a mirror image of the side shown; and,

FIG. 12 is a side elevational view rotated 90 degrees from FIG. 11, the side opposite being a mirror image of the side shown.

The broken line showing of a bag in FIG. 1 is for illustrative purposes only and forms no part of the claimed design.
